(57) **CLAIM**

The ornamental design for an easy feed pet bowl system as shown and described.

DESCRIPTION

FIG. 1 is a perspective view of a pet bowl feeding system including a single cavity bowl and a handle;

FIG. 2a is a perspective view of the system with the handle detached from the bowl;

FIG. 2b is a perspective view of the system with the handle rotated relative to the bowl;

FIG. 2c is a perspective view of the system, showing the handle being used to pick up the bowl;

FIG. 2d is a perspective view of the system, showing the handle being used to set the bowl down;

FIG. 2e is a perspective view of the system, with the handle rotated relative to the bowl; and

FIG. 2f is a perspective view of the system, with the handle detached from the bowl.

The figures illustrate an easy feed pet bowl system. The nature and environmental use of the claimed design is a pet bowl feeding system.

Features of the article that are not shown are disclaimed. Additionally, any features shown in broken lines are for illustrative purposes only and form no part of the claimed design.

1 Claim, 2 Drawing Sheets
